This technical drawing shows a cross-sectional view of a mechanical assembly. It features a central vertical rod with a slot 35. A horizontal plate 36 is positioned above the slot, and a circular component 40 is attached to its top. A vertical slot 37 is located on the right side of the assembly. The top edge of the assembly is marked with the number 41. The bottom edge is marked with the number 19. The entire assembly is labeled 'Fig. 6.11 41'.

UNITED STATES PATENT OFFICE

FOSS C. HUSH, OF LINCOLN, NEBRASKA

METER BOX

Application filed January 2, 1929. Serial No. 323,798.

It is the object of my invention to produce a box suitable for use in enclosing meters or other electrical apparatus to protect them from damage by the elements or by any unauthorized tampering. More specifically, it is my object to produce such a box which will fit closely against the associated pole on which it is mounted, which will be exceedingly strong and rigid, which will provide ample space for such apparatus or instruments as may be mounted within it, and which will be provided with a cover that when removed will render the contents of the box readily accessible.

I accomplish the above objects by forming the box of sheet metal with rigidly interconnected back and top portions, the back being shaped to provide an outwardly presented concave surface adapted to lie closely against the pole on which the box is mounted. The cover of the box forms the front, bottom, and sides thereof and is removably secured to the front of the top portion in such a manner that it may be swung in one direction to close the box and in the other direction to open it.

The accompanying drawing illustrates my invention: Fig. 1 is a view of the box with the cover closed, showing in dotted lines the pole on which the box is mounted; Fig. 2 is a view similar to Fig. 1, but with the box cover removed; Fig. 3 is a perspective view of the box cover; Fig. 4 is a vertical section through the center of the box, showing the cover slightly open; Fig. 5 is a horizontal section through the box; and Fig. 6 is a bottom plan illustrating the latching means by which the cover is held in place.

As previously stated, my box comprises two parts, a normally stationary part which is secured to a pole 10 and a removable part which forms a cover. The stationary part has a back 11 and a top 12, the back 11 being formed in cross-section, as is clear from Fig. 5, to provide an outwardly presented concave cylindrical surface adapted to fit rather closely against the surface of the pole 10. The top 12 is provided at its edges with depending flanges 13, and the back with for-

wardly projecting side flanges 14 and a bottom flange 15.

Desirably, the longitudinally extending cylindrical portion of the box-back 11 is of less width than the box, as is clear from Figs. 5 and 6. From the longitudinal edges of the curved part of the back there project inclined portions 11' which extend respectively to the rear edges of the side flanges 14. The back may be formed in this shape of sheet metal without the necessity for any reinforcement.

The cover forms the front 17, sides 18, and bottom 19 of the complete box, and is removably attached to the other part of the box as by means of outwardly bent fingers 21 which are secured to the front 17 near the top thereof and are received from the inside in slots 22 in the front flange 13. This method of mounting permits the cover to be swung outward, to a position somewhat beyond that illustrated in Fig. 4; and the fingers 21 can then be disengaged from the slots 22, to remove the cover entirely. As is clear from Fig. 2, the apparatus which may be mounted in the box, is thereby made accessible from the front, as well as from the sides and bottom.

Within the box, I provide a panel 24 on which may be mounted the apparatus that the box is to contain. This panel is secured to the back 11 by means of screws 25 on the vertical center line of the box and is conveniently supported at or near its edges by means of brackets 26 to which it may be secured by bolts 27.

The box may be provided with knock-outs in any desired location. As shown, I have shown two such knock-outs 30 in the inclined portions 11' of the box-back, two more knock-outs 31 in the box-top 12, and an additional pair 32 in the bottom flange 15. If the knock-outs 31 and 32 are provided, they are preferably located as close as practicable to the back and sides of the box, in order that any cable or conduit passing through them may extend without much deflection into the space 90 between the panel 24 and the box-back 11. To aid in thus disposing any cables or conduits, the corners on the panel 24 may be cut away, as is clear from Fig. 2.

When the cover is in place, the upper ends 100

of the front 17 and sides 18 are received within the flanges 13 which depend from the top 12. The vertical edges of the sides 18 are received within the vertical flanges 14, 5 and the bottom flange 15 extends outwardly over (inside of) the edge of the box-bottom 19, as is clear from Figs. 5 and 6. To secure the cover in closed position, I may mount on the under surface of the bottom 10 19 a pivoted latch 35 which co-operates with a stationary abutment 36 mounted on the bottom flange 15 of the box-back. The inter-engaging portions of the latch 35 and its associated abutment 36 are downwardly extending fingers or flanges 37 which have inclined portions as illustrated in Fig. 6 in order that a camming action tending to draw the cover tightly into place may be exerted when the latch is engaged. Desirably, the 15 flanges or fingers 37 are provided with aligned holes 38 for receiving the hasp of a padlock (not shown).

For the purpose of mounting the box on the pole 10, I may provide it with mounting members 40 and 41. As shown in the drawing, there is one mounting member 40, which is secured to the back of the box on the center line thereof and projects upwardly, its extending portion being provided with a 20 hole 42 for the reception of a suitable lag screw 43. Also as shown in the drawing, there are two of the mounting members 41. These are secured to the concave back 11 of the box and extend downwardly below the 25 bottom edge thereof, where they are provided with holes 44 for the reception of screws.

As has been pointed out above, the form of the cover and the type of its mounting permit the contents of the box to be made 30 readily accessible, in front, from both sides and from the bottom. By imparting a concave shape to the back of the box, I not only secure a more satisfactory mounting on the pole, but also impart considerable rigidity 35

to the box. Further, the concave portion of the back 11 of the box provides the vertically extending spaces or channels between the panel 24 and the box-back, thus making it 70 possible for connecting wires to be located therein away from the face of the panel 24.

I claim as my invention:—

1. A box, comprising a back and top rigid with each other, a cover formed to provide when in place a bottom, sides, and a front 75 for the box, and a panel within said box, said box-back being formed with a longitudinally extending, outwardly concave, cylindrical surface, forming within the box two longitudinally extending channels in rear of 80 said panel, the corners of said panel being cut away to provide access to said channels.

2. A box, comprising a back and top rigid with each other, a cover formed to provide when in place a bottom, sides, and a front 85 for the box, and a panel within said box, said box-back being formed with a longitudinally extending, outwardly concave, cylindrical surface forming within the box two 90 longitudinally extending channels in rear of said panel.

3. A box having a back, front, top, bottom, and side walls, the back of said box being formed with a longitudinally extending outwardly concave cylindrical surface of less 95 width than the box and with two inclined portions extending respectively from the longitudinal edges of said cylindrical surface to the rear edges of the box-sides, and a panel within the box, the cylindrical and inclined portions of the box-back forming within the box two longitudinally extending channels in rear of 100 said panel.

In witness whereof, I have hereunto set my hand at Lincoln, Nebraska, this 24th day of December, A. D. one thousand nine hundred and twenty-eight.

FOSS C. HUSH.
